UNITED STATES PATENT OFFICE

KENELM CHARLES APPLEYARD, OF BIRTLEY, COLIN WILLIAM HIGHAM HOLMES, OF LOW FELL, AND IVOR LLOYD BRAMWELL, OF BIRTLEY, ENGLAND, ASSIGNEES TO THE BIRTLEY IRON COMPANY, LIMITED, OF BIRTLEY, ENGLAND

SEPARATION OF DRY MATERIALS

Application filed January 4, 1929, Serial No. 330,364, and in Great Britain January 24, 1928.

This invention relates to the separation of dry materials. It is particularly directed to the separation of slate or other impurities or refuse from coal, that is, to the dry cleaning of coal, but it is not limited thereto, and includes the cleaning and grading of agricultural and mineral products and the like generally.

The object of the invention is to provide an improved apparatus for this purpose.

The invention will be described herewith mainly with reference to the cleaning of coal.

In previous apparatus of this type, where 15 riffles have been used, these have been made straight, both as regards the deck riffles and as regards the tailing riffles. Similar remarks apply to the banking bars against which the coal or the like becomes banked 20 during the process of separation. The result of this is that there is or is likely to be a check where angles are encountered.

The present invention consists in the substitution of curved members for straight 25 members in respect of one or more of the following features, viz., (a) deck riffles, (b) tailing riffles, and (c) banking bars.

The invention also consists in the improvements in and relating to the separation of dry 30 materials hereinafter described.

In the accompanying drawing

Figure 1 is a diagrammatic view of the 35 apparatus.

Fig. 2 is a sectional view on line 2-2 of Fig. 1.

In carrying the invention into effect according to the form illustrated by way of example, the table *a* of a coal cleaning machine is made with a banking bar *b*, curved through 40 part of its length, curved deck riffles *c* and a curved tailing bar or tailing riffle *d*. The banking bar *b* may be a continuous curve of substantial curvature for about the final one-third of the table, gradually merging 45 into a straight line at the part corresponding with the feed section, that is from the delivery end *e* to the feed end *f* as shown. The deck riffles *c* may be in two parts, namely the riffles of the feed section, and the riffles of 50 the tailing or delivery section, but angles

should be avoided in passing from one section to the other as far as possible. The tailing riffle *d* may be in the form of a continuous curve as shown, extending from the delivery end *e* to the feed end *f*, the part at the delivery end being of substantial curvature and merging into the riffles at the feed end, these riffles being of less curvature or in the limit becoming straight lines.

Referring to Figure 2 an air chest *g* is 55 formed of a bottom plate *h* and side plates *j*. Inside the chest are fixed supporting angles which carry the deck frame *k*, the deck surface being formed of an air pervious surface 1 fixed to stretcher bars or ribs *m*. Riffles *c* 65 are fixed to the surface of the deck, a space *n* being left between the ends of the riffles *c* and the banking bar *b* to form a shale path. An adjustable tailing riffle *d* is clamped to the deck by clamps *o* and bolts *p*.

Modifications may be made in the form described, for instance, a curved banking bar may be used with straight deck riffles, and with a tailing riffle in which the tailing and feed sections meet at an angle. A curved 75 tailing riffle may be used in combination with the ordinary banking bar, with either a curved banking bar, a curved tailing riffle or both.

The deck riffles may be of the usual type, 80 and of the same inclination, or of different inclinations in different parts, but preferably they are curved.

The invention may be applied to tables in which separation is effected by means of 85 vibration plus air pressure, and to those cases where no vibration is employed but is not necessarily limited to such use. It may also be applied in connection with separation or stratification by air pressure, 90 where air is employed for the purpose of loosening the bed of coal or the like, sometimes called static pressure, or where separation is effected in part or substantially by the velocity of the air.

The curvature of the parts referred to above, viz., banking bars, tailing riffles and deck riffles, may vary according to the results desired, and to the tables to which they are applied. In some cases they may be 100

cycloid or they may be parabolic in other cases.

The invention may be used in connection with the matters described in our co-pending applications Serial Nos. 330,363 and 330,365, filed Jan. 4, 1929. It is not limited to the tables referred to above and it may be applied to those tables where there is a double separation at the delivery end.

10 Having now described our invention, what we claim as new and desire to secure by Letters Patent is:—

15 1. An apparatus for the separation of dry material comprising an elongated table for the pneumatic separation of material consisting of a feed portion and a concentrating portion, a curved banking bar and a curved tailing riffle, the riffles of the concentrating portion being curved and disposed in acute 20 angular relation with respect to the tailing riffle.

25 2. An apparatus for the separation of dry material comprising an elongated table for the pneumatic separation of material consisting of a feed portion, a concentrating portion, and a delivery end, a curved banking bar and a curved tailing riffle extending along the longitudinal edges of the table, said banking bar and riffle gradually converging toward each other in a direction 30 from the feeding end to the delivery end of the table, the riffles of the concentrating portion being curved and disposed in acute angular relation with respect to the tailing 35 riffle.

35 In testimony whereof we have signed our names to this specification.

CERTIFICATE OF CORRECTION.

Patent No. 1,866,186.

July 5, 1932.

KENELM CHARLES APPLEYARD ET AL.

It is hereby certified that the above numbered patent was erroneously issued to "The Birtley Iron Company, Limited, of Birtley, England", as assignee of the entire interest in said invention, whereas said patent should have been issued to the inventors, said Appleyard Et al and The Birtley Iron Company, Limited, of Birtley, England, as assignee of one-fourth interest only, as shown by the records of assignments in this office; and that the said Letters Patent should be read with this correction therein that the same may conform to the record of the case in the Patent Office.

Signed and sealed this 22nd day of November, A. D. 1932.
